UNITED STATES PATENT OFFICE.

LOUIS P. VALIQUET, OF NEW YORK, N. Y., ASSIGNOR, BY MESNE ASSIGNMENTS, TO THE AMERICAN TYPEWRITER COMPANY, OF SAME PLACE.

TYPE-WRITING MACHINE.

SPECIFICATION forming part of Letters Patent No. 510,214, dated December 5, 1893.

Application filed March 31, 1892. Serial No. 427,150. (No model.)

To all whom it may concern:

Be it known that I, LOUIS P. VALIQUET, a citizen of the United States, and a resident of New York city, in the county of New York and State of New York, have invented certain new and useful Improvements in Type-Writing Machines, of which the following is a specification.

My invention relates more particularly to small, portable, low-priced typewriters, and has for its main object to provide a construction of machine of this description which may not only be economically made, but which is also durable and capable of performing first-class work, and to these ends and objects my invention consists in the various features of construction and combinations of devices hereinafter more fully described and particularly pointed out in the appended claims.

In the accompanying drawings, Figure 1 is a top plan view of a type writing machine embodying my improvements. Fig. 2 is a front elevation of the same. Fig. 3 is a side elevation looking from the left hand side. Fig. 4 is a vertical section taken at the line *v*, *v* of Fig. 1 with the parts in their normal positions. Fig. 5 is a horizontal section taken at the line *w*, *w* of Fig. 4 with the parts in their normal positions. Fig. 6 is a vertical section, similar to Fig. 4, but omitting some of the parts thereat, and exhibiting the feeding, locking and printing mechanisms in their working positions. Fig. 7 is a view similar to Fig. 5, showing the spacing and locking mechanisms in their working positions. Fig. 8 is a detail view, partly in section, of the feeding devices. Fig. 9 is a detail view of the driving-pawl and dog-carrying lever separated, and Fig. 10 is a detail view of the parts shown at Fig. 9 assembled together.

In the several views the same part will be found designated by the same numeral of reference.

1 designates the bed or base-plate, which may be of any desired size or design, that shown being preferred, however. At the rear of the base-plate is provided a series of lugs 2, which lugs are arranged in pairs opposite each other, and form a guide-way or straight path of travel for the paper-carriage. The

latter consists preferably of a comparatively wide bar 3, of a thickness about equal to the height of said lugs and provided at its front edge with a series of notches or cut-aways 4 55 formed with parallel sides and rounded bases and constituting a feed-rack. At each end of said bar is provided a support 5, which sustains a feed-roller 6, preferably rubber-covered, and a platen or impression-bar 7. 60

Secured upon the upper side of the rack-bar 3 is a bent metallic support 8, which at its upper end is curved relatively to the roller to form an arc-shaped paper-guide or deflector and a pressure-plate 9, which is arranged eccentrically of the center of the feed roller. The axle of the feed-roller is provided with a knob or hand wheel 10, by which the roller may be rotated and the paper fed in line-space direction, and said knob 70 or hand wheel is formed or provided with a series of depressions 11 arranged in line-space distance apart, into which is adapted to take a hold-fast dog 12 formed at the end of a plate secured by a screw 13 to the right hand standard. The device 9 at its lower rear end where it joins the bent plate 8, stands away from the surface of the feed-roller and forms therewith a mouth for the ready introduction of the paper from the rear of the machine. From this point the said device 9 gradually approaches the periphery of the feed-roller until at its upper forward edge it runs or bears in contact therewith, in order to afford a positive feed for the paper when introduced. Inasmuch as the upper forward edge of the device 9 terminates concentrically with the surface of the feed-roller, it has a tendency to guide or deflect the paper rearwardly in the direction of rotation of the feed-roller, 85 but this is overcome by having the upper portion of the feed-roller revolve in a circular groove 14 on the under side of the platen or impression-bar 7, and by beveling or slightly chamfering the lower front portion or edge of the latter, as seen at 15, adjacent to the upper end of the device 9, whereby when the edge of the paper to be printed is fed past the upper edge of the device 9, it is deflected or turned upwardly by said beveled or chamfered edge 15 and caused to ascend in a vertical path along the vertical face 16 of the bar 95 100

7 and between it and a shield-plate 17, which at its lower end is secured to the bottom of an upright or standard 18 preferably cast integral with the base-plate and centrally there-
5 of widthwise.

The paper-carriage is prevented from rising at its front side by reason of the fact that the front portion of the rack-bar slides in an under-cut or groove 19 formed at the bottom of the upright or standard, and is prevented from rising at its rear side by means of an overlapping plate or finger 20, detachably connected to the base-plate by a screw 21.

The paper-carriage is adapted to be fed
15 step-by-step toward the left by means of a driving-pawl 22, which is pivoted to a lever 23 that is fulcrumed at 24 upon the base-plate. The said lever is also provided with an integral tooth or dog 25 arranged substantially at
20 right angles to said lever, and adapted to engage with the teeth of the rack-bar to restrain the driving-pawl from feeding the paper-carriage more than one notch, tooth or letter-space at a time, as will hereinafter more fully
25 appear. To the free end of the lever 23, at which the driving-pawl is pivoted, is also pivotally-connected the rear forked end of a sliding rod 26, upon which is mounted a coiled spring 27, the rear free end of which bears
30 against both the driving-pawl and the lever 23, on opposite sides of the common pivot 28, and which at its front end bears against a lug 29 formed on the base-plate. The said lug is slotted to permit of the passage therethrough
35 of the said sliding rod 26, which at its free end is bent laterally and connected to a spacing lever or key 30 pivoted at 31 in downward extensions of the base-plate. By depressing said spacing-lever or key, the said
40 rod 26 is adapted to be drawn forwardly, compress its spring, vibrate the lever 23 and withdraw both the driving-pawl and the locking-dog from engagement with the teeth or notches of the feed-rack, the arrangement being such
45 that the moment the driving-pawl is freed from engagement with its tooth or notch, the spring 27 operates to vibrate said pawl about its pivot and throw its driving end one notch or tooth to the right, as indicated at Fig. 7, so
50 that upon release of the said spacing-lever or key, the said pawl will engage with the next succeeding tooth or notch of the rack, and by the distention of the spring 27 act to force or drive the feed-rack and the paper-carriage
55 on one notch or letter-space toward the left. At the same time the spring 27 operates to also vibrate the lever 23 about its pivot and cause the dog 25 thereon to engage with another tooth or notch of the feed-rack, and thus prevent the driving-pawl from feeding the carriage more than one notch at a time. The construction and operation are such that the driving-pawl acts on the left hand side of a notch in a direction toward the left, and the locking-dog acts
60 on the right hand side of another notch toward the right or in substantially a direction opposite to that of the driving-pawl. The

driving-pawl and the locking dog are relatively so arranged that immediately the pawl has moved the carriage a letter-space distance, the dog comes into engagement to effectually prevent any overthrow or extra movement of the carriage, due to sudden action or momentum of the feed. The upright or standard 18 is split or cut away vertically from its top to near its bottom, as indicated at 32, and through this cut-away the dog is arranged to work.

The type 33 are preferably made of soft rubber, and are molded upon or formed integral with a soft rubber or yielding support 34, which latter at or near its lower edge is secured to a vertically-arranged segmental metallic plate or support 35, which at its ends is secured by screws 36 to arms 37 extending from a hub or bearing 38. The rubber type-support or band 34 is connected to the segmental plate 35 in such a manner that the type stand well above the upper edge of said plate, and said type-support is preferably attached to said segmental plate by clamping its lower portion between the outer surface of said plate and the inner surface of a segmental metallic strip 39 of a length equal to that of the segmental plate, a series of small screws 40 passing forwardly through holes in said plate and coinciding holes in the rubber support and entering threaded holes in the outer clamping strip 39. The said hub or bearing 38 is mounted upon a journal or pivot 41 having a shoulder 42, and secured to the base-plate by a washer 43 and a screw 44. The screw passes through a slot 45 in the base-plate, which enables the journal or pivot and parts carried thereby to be properly adjusted to effect the best results in the printing. By moving the pivot back or forth, the type are brought nearer to or farther from the platen, as may be necessary.

The upper end of the pivot or journal is threaded to receive a threaded nut 46, which clamps upon the bearing or hub the outer end of an indicator or pointer 47, the said outer end having a large perforation centrally to fit over the upper end of the journal, and having also two diametrically opposite smaller perforations to fit over two small pins 48 projecting upwardly from the hub, in order to prevent the said indicator or pointer from having any motion independent of the said hub or bearing.

The indicator is preferably spear-shaped at its outer end and is formed with a cup or depression 49 to receive the finger of the operator and facilitate the vibration of the indicator and the oscillation of the type.

In front of the feed-rack and near each side of the base-plate are provided two posts 50, which support a top-plate 51 that bears the keyboard or index-plate 52. The said top-plate is preferably formed with a segmental depression 53 adapted to receive the index which is correspondingly shaped and printed on paper or card board and preferably cov-

ered with a piece of glass, celluloid, or other transparent medium 54. The top-plate is provided with a sunken portion 55 between the journal and the index to form a rest for the hand, and also to facilitate the movement of the hand during the swinging or vibration of the indicator, which as shown is arranged to overlie the top-plate. Upon each of said posts 50 is secured by screws 56, an arm or bracket 57 which at its free end supports an inking-roller or equivalent device 58 adapted to impart ink to the type.

By swinging the indicator any of the type may be brought to the impression or printing point. The type are caused to make their impressions on the paper by the following means: Pivoted at 59 in the upright or standard 18 is a vertically-arranged plate 60 which works in the slot 32, and which at its upper end is provided with a type-presser 61. At 62 is pivoted or loosely connected the rear end of a printing lever 63 which is fulcrumed at 64 in a post 65 on the base-plate, and which terminates at its outer end on the left hand side of the machine preferably, in a finger-piece 66. To said plate 60 is pivoted at 67 an arm 68 which extends forwardly and downwardly and terminates in a fork 69 which embraces the sliding rod 26 and stands against a stop or projection 70 on said rod. By this construction and arrangement when the finger-piece 66 of the printing lever is depressed the plate 60 is turned about its pivot as a lever, and the type-presser is caused to move rearwardly and the arm 68 forwardly, these devices being on opposite sides of the pivot of said plate, with the result that the type-presser acts to force the type behind which it plays, through an opening 71 in the shield, and cause its face to leave an impression upon the paper, and simultaneously the arm, by its forward movement, operates to push the spring-actuated rod 26 forwardly and cause the driving-pawl and locking-dog to both disengage from the feed-rack. Upon releasing the printing lever, the spring 27 operates to return it, the plate 60, and the pawl and dog to their normal positions, the pawl at the same time acting to feed the carriage one letter-space, and the dog to limit the feed. The said plate 60 is provided with a nose or projection 72, between its pivot and the type-presser, which is adapted to enter any one of a series of openings 73 formed in the segmental-plate below the type band. Each of said openings is arranged directly under and in line with one of the type, with the center of the opening coincident with the center of the type, and by this arrangement the nose or projection is adapted to lock the segment and body of type securely in position during the printing movement, and thus insure absolutely accurate spacing between letters or words.

At Fig. 6 the type-presser is shown as having forced the type to the platen, the rubber band or support yielding to permit of the

same; the nose or projection is shown as locked, with the perforated type segment to hold the same against lateral movement; and 70 the carriage feed and locking devices are shown as retracted ready to advance the carriage a letter-space distance upon the return of the type presser and segment-locking projection to their normal positions.

The type are arranged in one continuous row or in one horizontal plane, and the series of segment notches or slots are similarly arranged, while the characters on the keyboard or index arranged in a horizontal plane, are 80 disposed in two concentric arcs for the purpose of obtaining characters of a size considerably larger than that of the types themselves, in order that the operator may more readily operate the machine without unduly 85 tiring the eyes. From the center of each character on the back row extends rearwardly a short radial line 74, and from the center of each character on the front row extends rearwardly a longer radial line 75, the characters 90 in both said rows being arranged to alternate so that each character of the lower row stands in a line midway between two characters on the upper row, and the two series of radial lines being so arranged that beyond the rear 95 row of characters they lie side-by-side at equal distances apart and corresponding to the distance apart from center to center of the types.

From what has already been said the operation of the machine will be readily understood, but I shall add the following brief description thereof: If it be desired to write the word "The," the finger may be placed in the cup or depression 49 and the indicator swung toward the right (Fig. 1) until the pointer 100 registers with the longer radial line extending to the capital letter "T." By this movement it will be understood that the capital type "T" is brought to the printing point, the type being of course arranged relatively 105 to the arrangement of the characters on the index. The printing lever is now depressed at its outer end, the plate 60 is vibrated, the nose or projection 72 caused to enter the opening directly beneath the type "T," the 110 type presser 61 caused to press or force the capital "T" type through the opening in the shield against the paper, and the driving-pawl and locking-dog caused to withdraw 115 from the rack-bar through the movements of 120 the arm 68 and rod 26. Upon releasing the printing lever the parts all return to their first positions, and the carriage is moved a letter-space distance by the driving-pawl. The indicator is then again swung farther to 125 the right until the pointer thereon registers with the short line radiating from the lower case "h" to bring that type to the printing point. The printing lever is again depressed at its outer end, and the actions of the printing, locking and feeding devices are repeated. The indicator is then swung toward the left 13 until the pointer registers with the longer line radiating from the lower case "e" to bring

that type to the printing point and the printing lever is again depressed as before. It is intended that the right hand shall operate the indicator to bring the type to printing position, and that the left hand shall actuate the printing lever to effect the impression, locking, and feeding. To space between words, the space-key or lever 30 is actuated, while the indicator and printing lever remain at rest. The printing lever may be provided with a spring, as shown at 76. The shield operates to prevent the type-presser from printing either of the adjacent type simultaneously with that one it is desired to print. The soft rubber, yielding, elastic support permits the type-presser to readily and squarely present the type to the paper, and upon recession of the type-presser to return the type by reason of its inherent resiliency. The type-presser is purely what its name indicates. It operates simply to effect impressions by pressure instead of a blow. To return the carriage for the beginning of a new line, the space-key is depressed which releases the driving-pawl and locking dog.

What I claim as new, and desire to secure by Letters Patent, is—

1. In a type writing machine, the combination with a paper-carriage having a rack-bar, of a lever having a rigid locking dog, a driving pawl attached to the free end of said lever, a sliding rod pivoted to said lever, and a spring pressing against both said lever and said driving-pawl.

2. In a type writing machine, the combination with a paper-carriage having a rack-bar, a lever, a driving-pawl pivoted to the free end of said lever, a sliding rod pivoted to said lever, and a coiled spring on said rod pressing at one end against the said lever and also against said driving-pawl, whereby when said rod is retracted the said spring operates to vibrate said driving-pawl, and when said rod is released the said spring operates to vibrate said lever toward said rack and cause the driving-pawl to engage a notch thereof and simultaneously vibrate about its pivot and push or drive the carriage a letter-space distance.

3. In a type writing machine, the combination of a paper-carriage having a rack bar, the lever 23 arranged substantially parallel with said rack-bar, the driving pawl 22 pivoted to the free end of said lever, the rigid dog 25 made integral with said lever and arranged between said driving pawl and the pivot of the lever, the said pawl and the said dog being arranged to simultaneously engage with and be retracted from said rack, a spring-pressed rod attached to said lever, and a spacing lever connected to said spring-pressed rod.

4. In a type writing machine, the combination of a paper-carriage having a rack-bar, a lever carrying a dog a driving-pawl and a sliding rod pivoted to said lever, a coiled spring on said rod bearing at one end against

an abutment and at its other end against both said lever and said pawl, and means for retracting said rod.

5. In a type writing machine, the combination of a paper-carriage having a platen, a circular rotatory plate provided with a series of notches or slots, a soft rubber type-support attached to said plate and provided with a circular row of types arranged in line with said notches or slots above said plate, a type-presser arranged above said plate, a locking pin or projection to engage said notches or slots, and means for simultaneously moving said type-presser and said pin or projection to cause the former to press the type against the paper on the platen, and the latter to engage one of the said notches or slots and lock the said plate and its accessories.

6. In a type writing machine, the combination of a paper-carriage having a platen, a circular rotatory plate having a series of notches or slots, a soft rubber type-support, attached to said plate, provided with a circular row of types arranged in line with said notches or slots and above said plate, a vertically-arranged pivoted plate or lever provided with a type-presser and a locking pin or projection, means for actuating said plate or lever, a carriage feed mechanism, and a connection between said plate or lever and said feed-mechanism.

7. In a type writing machine, the combination of a paper-carriage having a platen, a circular rotatory plate, a series of notches or slots, a soft rubber type-support attached thereto and provided with a circular series of types arranged in line with said notches or slots and above said plate, a vertically-arranged pivoted plate or lever provided on one side of its pivot or fulcrum with both a type-presser and a locking pin or projection, a lever for actuating the said plate or lever, a carriage feed-mechanism, and an arm connected at one end to the opposite side of the pivot or fulcrum of said plate or lever, and at its other end to the said feed-mechanism.

8. In a type writing machine, the combination of a paper-carriage having a platen, a segmental rotatory plate provided with a series of notches or slots, a soft rubber type-support attached to said plate and provided with a circular series of types arranged in line with said notches or slots and above said plate, a vertically-arranged pivoted plate or lever provided with a type-presser and a locking pin or projection on one side of its pivot or fulcrum, a printing lever connected to said plate or lever to actuate the same, an arm connected at one end to the opposite side of the fulcrum of said plate or lever and at its opposite end to a horizontally-arranged sliding spring-actuated rod carrying at its free end a set of carriage driving and locking devices.

9. In a type writing machine, the combination of a paper-carriage having a platen and a rack-bar, a bed-plate, a slotted upright or

standard, a shield attached thereto and provided with a type-opening, the segmental rotatory notched or slotted plate, the soft rubber type-carrying band, the plate or lever 60 provided with a type-presser and a locking pin or projection pivoted to work in the slot of said upright or standard, the printing lever, the arm 68 the sliding rod 26, the lever 23, the pawl 22, the dog 25 and the spring 27.

10. In a type writing machine, the combination with the paper-carriage having a platen, of a stationary index plate, the journal 41, the hub or bearing 38, the arms 37, the segmental notched or slotted plate, the segmental soft rubber type band attached to said plate, a type-presser, means for locking the segmental-plate and type-band, an indicator connected to said hub or bearing to rotate said segment and type-carrying band, a printing lever independent of the said indicator, and intermediate means for transmitting the motion of said printing lever to the type-presser and locking means, after the indicator has been turned and the desired type brought to the printing position.

11. In a type writing machine, the combination of the pivot or journal, the hub or bearing, the outwardly-extending arms, the vertically-arranged segmental-plate, the vertically-arranged soft rubber type-carrying band attached to said plate, the horizontally - arranged stationary overlying index plate, and the indicator having a finger-cup and connected directly to said hub or bearing, the type, the characters on the index plate, and the indicator all being arranged radially of the pivot or journal and in rear thereof.

12. In a type writing machine, the combination of a paper - carriage, a vertically - arranged, pivoted segmental plate, a vertically-arranged soft-rubber type-carrying band attached thereto, an indicator connected to said segmental plate at the pivot of the latter and projecting rearwardly, a stationary horizontal top-plate arranged between the pivot of the segmental plate and the paper-carriage and provided on top with a segmental index or dial arranged wholly between the pivot of the indicator and the carriage, whereby the indicator is enabled to work entirely on the rear side of its pivot, thus enabling the finger controlling the indicator to move the same relatively to all of the characters on the index or dial while the hand is at rest, or without moving the arm.

13. In a type writing machine, the combination with a paper-carriage, a vertically-arranged, pivoted segmental plate having a vertically arranged soft - rubber type - carrying band attached thereto, a fixed top-plate arranged over said segmental plate and in rear

of the pivot thereof, a segmental index or dial arranged on said top-plate, an indicator pivoted concentrically of said segmental plate and in front of the top-plate and working always on the rear side of its pivot, a type presser, a carriage feeding mechanism and a printing lever arranged to operate independently of the segmental plate and the indicator and adapted to actuate the said type 70 presser and said spacing mechanism after the indicator has been moved and the desired type brought thereby to the printing point.

14. In a type writing machine, the combination with a paper-carriage, a spacing-mechanism therefor including a separate spacing key, a vertically arranged, pivoted segmental plate carrying a soft-rubber type-band, a vertically-arranged pivoted type presser, an arm 68 connecting said type presser to the spacing mechanism, a printing lever also connected to said type presser, a top plate carrying a segmental index or dial, and a rearwardly projecting indicator pivoted in front of said top-plate and coincidently with the 85 pivot of the segmental type-carrying plate.

15. In a type writing machine, the combination with a paper-carriage, a vertically arranged, pivoted segmental plate carrying a type - band and provided with a series of 90 notches, and a vertically-arranged, pivoted plate or lever carrying a type presser and a locking pin or projection on one side of its pivot or fulcrum, a printing lever connected to said plate or lever on the same side of the 95 pivot or fulcrum, an arm connected at one end to the opposite side of the pivot or fulcrum of said plate or lever and at its other end to a horizontally-arranged sliding spring-actuated rod carrying at its rear end the carriage driving and locking devices.

16. In a type writing machine, the combination of a paper-carriage having a feed rack, the teeth of which have parallel sides and rounded bases, a spring-actuated lever arranged substantially parallel with said rack, a driving pawl pivoted at the free end of said lever, and a locking dog made integral with said lever and arranged between the said pawl and the pivot of said lever, the said 105 pawl and dog being arranged to simultaneously and normally engage the teeth of said rack and to each exert a force in a direction opposite to that of the other during a spacing movement.

Signed at New York city, in the county of New York and State of New York, this 28th day of March, A. D. 1892.

LOUIS P. VALIQUET.

Corrections in Letters Patent No. 510,214.

It is hereby certified that in Letters Patent No. 510,214, granted December 5, 1893, upon the application of Louis P. Valiquet, of New York, N. Y., for an improvement in "Type-Writing Machines," an error appears in the printed specification requiring the following correction: In lines 104-5, page 5, the words "and rounded bases" should be stricken out; and that the Letters Patent should be read with this correction therein that the same may conform to the record of the case in the Patent Office.

Signed, countersigned, and sealed this 12th day of December, A. D. 1893.

[SEAL.]

JNO. M. REYNOLDS,
Assistant Secretary of the Interior.

Countersigned:

JOHN S. SEYMOUR,
Commissioner of Patents.
